COMBINED SHIPPING AND DISPLAY CARTON FOR HAIR NETS

Lazare Mayer, 200 E. Chestnut St., Chicago, Ill.

Filed Oct. 6, 1959, Ser. No. 57,825

Term of patent 14 years

(Cl. D58—12)

Fig. 1 is a perspective view of the combined shipping and display carton for hair nets embodying my new design;

Fig. 2 is a side view thereof.

The rear and side not shown are substantially plain.

The dominant features of my design reside in the portions shown in the full lines.

I claim:

The ornamental design for a combined shipping and display carton for hair nets, substantially as shown and described.
